FLUID LIFT

Mark P. Burke, Long Beach, Calif.

Application April 21, 1938, Serial No. 203,451

18 Claims. (Cl. 103—234)

This invention relates to a deep well pumping mechanism, and particularly pertains to a fluid lift of the general type shown in U. S. Letters Patent No. 1,827,066 issued to me October 13, 1931, entitled "Gas lift means."

In pumping a liquid from a well by the use of a fluid under pressure, such as gas, it is desirable to provide means for alternately allowing liquid to accumulate in a well to a desired depth and then to introduce gas under pressure to lift the accumulated quantity of liquid irrespective of the degree of submergence of the lower end of the flow pipe within the accumulated liquid of the well. It is the principal object of the present invention to provide a simple valve mechanism which may be connected with the flow pipe at the lower end of the well, which will act under pressure to direct said fluid against and beneath an accumulated quantity of liquid to elevate this quantity of liquid through the flow pipe, and to act automatically to interrupt the flow period when a predetermined accumulated quantity of liquid has been elevated through the flow pipe.

The present invention contemplates the provision of a flow pipe adapted to be lowered into a well casing and carrying a packer which engages the casing and packs off a pumping chamber at the bottom of a well, said flow pipe also carrying a valve mechanism which acts automatically due to changes in equilibrium of gas and a liquid to intermittently pump slugs of liquid from a well.

The invention is illustrated by way of example in the accompanying drawings in which:

Figure 1 is a fragmentary view in section and elevation showing the application of the present invention to a well.

Fig. 2 is an enlarged view in central longitudinal section showing the automatic intermitter valve in its normal closed position.

Fig. 3 is a view similar to Fig. 2, showing the intermitter valve opened.

Fig. 4 is a view in transverse section through the intermitter valve structure as seen on the line 4—4 of Fig. 3 and as viewed in the direction of the arrows.

Referring more particularly to the drawings, 10 indicates a well casing; 11 is a perforated casing screen at the bottom of the well; 12 indicates a flow pipe which extends downwardly through the well casing and terminates within or adjacent to the perforated screen 11. The flow pipe is sealed in at the top of the casing 10 by a suitable instrumentality 13; a gas inlet pipe 14 communicates with the interior of the casing 10 at a point

above the level of the ground and is in communication with suitable gas pressure flow and regulating means in a part of the present invention.

Carried upon the flow pipe 12 and positioned at a suitable depth in the well is a casing packer 15, which forms a seal in the well and creates a lower chamber 16 within which liquid accumulates and an upper chamber 17, through which gas may flow downwardly within the casing 10 and around the flow pipe 12 for a purpose to be hereinafter described. Mounted within the flow pipe 12 and here shown as being disposed at a level above the level of the packer 15 is an automatic intermitter valve 18. By reference to Figs. 2 and 3 it will be seen that this valve includes an outer tubular valve housing 19 having an enlarged upper portion 20 which fits within the flow pipe 12 and is here shown as being welded in position. A downwardly projecting portion 21 of the valve housing 19 is of reduced diameter as compared with the upper portion 20 and provides an annular fluid space 22 in the upper end of a liquid chamber 23.

Extending through the upper portion 20 of the housing 19 is a plurality of longitudinally aligned ducts 24, which establish uninterrupted communication between the chamber 23 and the length of flow pipe 12 above the valve 18. The upper enlarged end 20 of the housing 19 is formed with a central bore 25, which terminates in a square shoulder 26 and an inclined valve face 27. The lower portion 21 of the housing 19 is formed with a bore 28, which is a continuation of a central aligned passageway through the housing and which bore is of reduced diameter as compared with the upper communicating bore 25. The upper end of the bore 28 terminates with the downwardly and inwardly inclined valve face 27 and the lower end of the bore terminates with an internally threaded portion 29, which receives a threaded adjusting plug 30.

The plug 30 provides a seat for a compression spring 31, which is positioned within the bore 28 and upon which a balanced valve element 32 rests. This valve element has a lower cylindrical portion 33 which fits into the bore 28 with a sliding fit. A plurality of sealing grooves 34 is formed around the outer circumference of the portion 33 and tends to form a liquid seal between this circumference and the bore 28.

Intermediate in the length of the valve element 32 is an enlarged portion 35 which is formed at its lower end with an inclined shoulder 36 designed to abut against the face 27 of the valve housing

and to form a fluid seal therewith when so positioned. The upper shoulder 37 of the enlarged valve portion 35 is oppositely tapered from the shoulder 36 and abuts against an inclined valve face 38 of a valve seat sleeve 39. This valve seat sleeve has a central bore 40 extending upwardly therethrough which is in longitudinal alignment with and the same diameter as the bore 28 in the lower extension 21 of the valve housing 19. The upper end of the bore 40 has an enlarged undercut recess 41 therein, which provides an overhanging downwardly and outwardly inclined valve face 42, terminating in an upper central opening 43. An inclined valve face 44 is formed on the upper end of the valve element 32 and abuts against the face 42 when the shoulder 37 of the valve portion 35 abuts against the face 38 of the valve seat 39.

Interposed between the shoulder 26 of the valve housing and the lower end of the valve seat 39 is a spacing ring 45, which positions the valve faces 27 and 38 in such a spaced relation to each other as to permit a predetermined amount of longitudinal movement of the valve element 32 within the housing 19 while the shoulder 37 moves from an abutting position against the face 38 until the shoulder 36 seats against the face 27.

As shown particularly in Fig. 4 of the drawings a plurality of radially disposed ducts 46 are formed through the wall of the flow pipe 12, the upper portion 20 of the housing 19 and the wall of the valve seat 39. By reference to Figs. 2 and 3 it will be seen that these ducts 46 establish communication between the gas chamber 17 and the recess 41 formed within the valve seat 39 and that when the movable valve element 32 is in its lowermost position communication between the recess 41 and the interior of the portion of the flow pipe 12 above the valve structure will be made.

The lower end of the valve housing 19 is provided with a threaded plug 19' which closes the opening at the bottom of the bore 28. A central passageway 47 is formed within the valve element 32 and a central passageway 30' is formed within the plug 30. Fluid can, therefore, fill the space within the bore from the plug 19' upwardly and into the passageway 47 within the valve element. Formed through the plug 19' is a passageway 48 which receives a check valve structure 48'. This structure will permit an outflow of fluid from the bore 28 and the passageway 47 within the valve element while preventing an inflow of fluid through the valve.

In operation of the present invention a suitable fluid pressure regulating means is connected with the pipe 14 and is interposed between this pipe and a suitable source of fluid under pressure. The flow pipe 12 is lowered into the well with its packer 15 and is set in position. Mounted adjacent to the lower end of the flow tube and carried thereby is a standing valve 49 which permits liquid to enter the flow tube but not to exit therefrom. The spring 31 of the valve has been adjusted by the adjusting nut 30, so that the valve element 32 will be held in its uppermost position and with a fluid seal occurring between the faces 42 and 44 and the faces 37 and 38. When the packer 15 has been properly set in the well casing 12 the lower liquid chamber 16 will be sealed off at the bottom of the well casing and the gas chamber 17 will be sealed off in area between the packer and the top of the well.

When a predetermined level of liquid has been reached gas under pressure is delivered to the

casing 10 through the pipe 14. This gas passes downwardly within the chamber 17 and will be forced inwardly through the radial passageways 46 to the recess 41 within the valve seat 39. The further flow of the gas will be interrupted due to the fact that the valve 32 is in its closed position. When, however, the accumulated column of liquid within the length of flow pipe 12 above the intermitter valve structure is of sufficient head to exert a pressure against the end face of the valve member 32, through the central opening 50 in the top of the valve seat structure 39, to overcome the force of the spring 31 the valve element 32 will move downwardly to its opened position, at which time the shoulder 36 on the valve element will abut against the face 27 in the valve housing and seal off the bore 28 from the gas under pressure, which is being delivered through the chamber 17. This gas will pass through the radial passageways 46 and the recess 41 into the central opening 50 of the member 39 and will then be disposed beneath the accumulated column of liquid which is within the length of flow pipe above the valve structure.

Attention is directed to the fact that the volume of gas delivered to the valve structure is such as to insure that the gas will not aerate the liquid, but will move beneath it and lift the accumulated body of oil as one mass. This lifting action will continue until the weight of the liquid mass imposed upon the valve element 32 has diminished to a point where the spring 31 will move the valve element 32 to its upper and closed position. The flow of gas will thus be interrupted and another volume of oil may then build up within the flow pipe 12 until its weight is sufficient to open the valve 32 again.

Attention is directed to the fact that during the period following the time when the slug of liquid has been forced from the well the fluid pressure of the operating fluid will have been reduced by the escape of the fluid through the flow pipe 12 and the valve will have been closed. At this time and before the liquid to be pumped has again entered the liquid chamber 23, the fluid pressure around the valve structure and within the bore 28 and the passageway 47 will be reduced substantially to atmospheric pressure. The check valve 48' mounted at the bottom of the bore 28 will then permit any excessive fluid pressure within the bore 28 to equalize with the pressure surrounding the valve since the valve 48' may open to relieve the pressure within the valve. As here provided, the closed chamber 23 with its equalizing check valve 48' makes it possible to establish a predetermined resistance against the movable valve element 32 by the spring 31 and the adjusting nut 30. It will be recognized that the spring 31 is of a strength to support the weight of a column of fluid accumulated in the tubing 12 and above the valve element. Thus, for example, if the determined weight of an accumulated column of liquid was equal to 300 pounds per square inch against the movable element 32 through the opening 43 the strength of the spring 31 would of necessity be more than 300 pounds and would be set by adjustable nut 29 to yield at 300 pounds. In the course of operation of the movable valve element 32 fluid may leak around the valve element and accumulate within the bore 28 compressing the air in bore 28 and passageway 47. For this reason the port 48 and the check valve 48' have been mounted at the lower end of the bore 28. It will be seen that the port 48 and the check valve 48' will allow the

compressed air in the chamber 28 and the passageway 47 to exhaust any accumulation of fluid that may have leaked thereinto during the cycle of operation of the valve element 32, and that this exhaust will take place at the low point in the pumping cycle so that there will not be undesired pressure resistance against the movable element 32, making it possible to set the spring 31 for a predetermined pressure and also prevent valve element 32 from becoming fluid locked. At the low point in the pumping cycle the entrapped and compressed fluid within bore 28 will be exhausted until the pressure within the bore 28 substantially equals the pressure outside of valve 48' at which time the valve 48' will close. It will be seen that the port 48 and check valve 48' allow the chamber 28 and passageway 47 to exhaust any accumulation of fluid that may have leaked thereinto during each cycle of operation of the valve element 32. When the valve element 32 is thereafter forced to its opened position by the weight of the accumulated liquid column in flow pipe 12 the pressure operating fluid will be again directed beneath and against the liquid column and the end of the valve which is exposed through the central opening 43 of the housing. The valve element 32 will then instantly move to its opened position. This will simultaneously act to move the shoulders 27 and 36 of the housing and valve, respectively, to abutting positions, as shown in Fig. 3 of the drawings, so that the bore 28 and the space 47 will be sealed against the effect or action of fluid under pressure which might otherwise be forced downwardly around the upper portion of the valve stem and in the upper bore 40 while the shoulders 37 and 38 are separated. When the valve is opened the valve element 32 has exposed a larger area of the upper end of the valve element as it has moved from its seat 42, an excess pressure will be exerted upon the valve element to retain it in its opened position until the slug of liquid has been ejected from the well. When the valve is closed, as shown in Fig. 2 of the drawings, the movable element 32 is seated and fluid pressure exerted through the ducts 46 is neutralized against the sides of the movable element. A column of liquid accumulates within the flow tube to impose a hydrostatic head upon the exposed end of the movable element 32. This hydrostatic head is supported by the movable element 32 and the spring 31 until the column of fluid provides a pressure sufficient to overcome the pressure of the spring, at which time the movable element 32 will be lowered so that the fluid pressure through ducts 46 may be directed upwardly over the end of the movable element 32 and through the opening 43 to a point beneath the slug of liquid which has accumulated in the pipe 12. While this action takes place pressure will be at a maximum, and it may occur that fluid may be forced downwardly around the movable element 32 to fill the bore 28 and the bore 47. At the end of the pumping cycle when the slug has been discharged from the well fluid pressure will be at a minimum, and in the event the accumulated liquid within the bore 28 and the bore 47 exerts a pressure greater than the pressure of the fluids within which the valve structure is enveloped the check valve 48' will open to permit this fluid to be discharged. Instantly, however, when the pressure on the outside of the valve 48' exceeds the pressure on the inside of the valve structure the valve 48' will close. This makes it possible for a completely submerged flow valve to be operated in a tubing and to insure that the

flow valve will not at any time become fluid locked.

Attention is directed to the fact that this invention is particularly novel in that it provides a valve structure which will function under the action produced by the pressure created, a pressure operating fluid and a definite column of liquid within which the pump is submerged and by which action a slug of liquid will be ejected from the well. As has been previously disclosed, this is brought about by the balancing and overbalancing of pressures which exist between a constant fluid pressure and the pressure of a predetermined liquid column as controlled and regulated by the valve structure here disclosed.

It will thus be seen that the structure here disclosed provides means including a single string of pipe which may be introduced into a well casing to a selected depth and by which a continuous supply of a fluid under pressure may be intermittently released to elevate masses of oil to the top of the well by an automatic operation depending exclusively upon the accumulation of a predetermined quantity of oil within the flow pipe and without reference to any timing of the gas supply delivery or the valve actuation.

While I have shown the preferred form of my invention as now known to me, it will be understood that various changes may be made in the combination, construction and arrangement of parts by those skilled in the art without departing from the spirit of the invention as shown.

Having thus described my invention, what I claim and desire to secure by Letters Patent is:

1. A fluid lift apparatus for wells comprising a casing, a flow tube extending downwardly therein, a foot valve in the bottom of said flow tube, said lower end of the flow tube being submerged in the liquid of the well, means for packing off the space between the casing and the flow tube to form a liquid pressure chamber at the bottom of the well and a pressure fluid space thereabove, a valve structure disposed within the flow tube at a level above the packing means, said valve structure including a fixed element having liquid ports therefrom and through which liquid may freely flow from the portion of the flow tube below the valve into the portion of flow tube thereabove and other ports in said valve element through which fluid under pressure from the casing may flow into the portion of flow tube above the valve when the valve is open, a valve element located within the valve structure and normally closing the ports for the fluid under pressure and moving to an open position when a predetermined head of liquid has accumulated within the flow tube above the valve and beneath which leakage liquid collects within the valve structure and means acting at the low pressure point in the pumping cycle to clear the valve structure of fluid and to prevent the valve from becoming fluid locked.

2. A fluid lift apparatus for wells comprising a casing, a flow tube extending downwardly therein, a foot valve in the bottom of said flow tube, said lower end of the flow tube being submerged in the liquid of the well, means for packing off the space between the casing and the flow tube to form a liquid pressure chamber at the bottom of the well and a pressure fluid space thereabove, a valve structure disposed within the flow tube at a level above the packing means, said valve structure including a fixed element having liquid ports therefrom and through which liquid may freely flow from the portion of the flow tube below the valve into the portion of flow tube there-

above and other ports in said valve element through which fluid under pressure from the casing may flow into the portion of flow tube above the valve, a valve element located within the valve structure and normally closing the ports for the fluid under pressure and moving to an open position when a predetermined head of liquid has accumulated within the flow tube above the valve and beneath which leakage liquid collects within the valve structure, means acting within the valve structure at the low pressure point in the pumping cycle to vent fluid from the structure and to prevent the valve from becoming fluid locked, and yieldable adjustable means normally resisting the opening of the valve until a predetermined liquid column has accumulated thereabove.

3. A fluid lift apparatus for wells comprising a casing, a flow tube extending downwardly therein, a foot valve in the bottom of said flow tube, said lower end of the flow tube being submerged in the liquid of the well, means for packing off the space between the casing and the flow tube to form a liquid pressure chamber at the bottom of the well and a pressure fluid space thereabove, a valve structure disposed within the flow tube at a level above the packing means, said valve structure including a fixed element having liquid ports therefrom and through which liquid may freely flow from the portion of the flow tube below the valve into the portion of flow tube thereabove and other ports in said valve element through which fluid under pressure from the casing may flow into the portion of flow tube above the valve, a valve element located within the valve structure and normally closing the ports for the fluid under pressure and moving to an open position when a predetermined head of liquid has accumulated within the flow tube above the valve and beneath which leakage liquid collects within the valve structure, means acting within the valve structure at the low pressure point in the pumping cycle to vent fluid from the structure and to prevent the valve from becoming fluid locked, yieldable adjustable means normally resisting the opening of the valve until a predetermined liquid column has accumulated thereabove, and means forming a part of the valve whereby the area of the pressure surface exposed to the head of liquid within the tube will be increased when the valve opens to thus tend to maintain the valve in an opened position during the pumping period.

4. In a fluid lift for wells, the combination of a chamber sealed off at the bottom of a well and submerged within the liquid of the well, a flow tube extending into said chamber, a foot valve in said flow tube, a valve structure disposed in the flow tube at a depth lower than the level of liquid within a well, means incorporated in said valve structure for permitting a continuous flow of liquid to flow upwardly through the flow tube and around the valve, means for introducing a fluid under pressure into the valve structure and whereby said fluid may be delivered beneath the column of liquid accumulated within the flow tube above the valve structure, a valve element located within the valve structure and normally preventing the flow of said fluid under pressure and acting to alternately open and close as affected by variation in the accumulation of liquid within the flow tube and above the valve and beneath which valve leakage fluid may be entrapped and means acting at the low point in the pumping cycle to establish equilibrium in fluid pressure to

prevent a greater fluid pressure within the valve structure than prevailing within the tube.

5. In a fluid lift for wells, the combination of a chamber sealed off at the bottom of a well and submerged within the liquid of the well, a flow tube extending into said chamber, a foot valve in said flow tube, a valve structure disposed in the flow tube at a depth lower than the level of liquid within a well, means incorporated in said valve structure for permitting a continuous flow of liquid to flow upwardly through the flow tube and around the valve, means for introducing a fluid under pressure into the valve structure and whereby said fluid may be delivered beneath the column of liquid accumulated within the flow tube above the valve structure, a valve element located within the valve structure and normally preventing the flow of said fluid under pressure and acting to alternately open and close as affected by variation in the accumulation of liquid within the flow tube and above the valve and beneath which leakage liquid collects within the valve structure, means incorporated within said valve structure for normally establishing a fluid pressure within the valve which is not in excess of the fluid pressure within the flow tube, and means whereby the valve will be over-balanced by the fluid when it is open.

6. In a fluid lift for wells, the combination of a chamber sealed off at the bottom of a well and submerged within the liquid of the well, a flow tube extending into said chamber, a foot valve in said flow tube, a valve structure disposed in the flow tube at a depth lower than the level of liquid within a well, means incorporated in said valve structure for permitting a continuous flow of liquid to flow upwardly through the flow tube and around the valve, means for introducing a fluid under pressure into the valve structure and whereby said fluid may be delivered beneath the column of liquid accumulated within the flow tube above the valve structure, a valve element located within the valve structure and normally preventing the flow of said fluid under pressure and acting to alternately open and close as affected by variation in the accumulation of liquid within the flow tube and above the valve and beneath which leakage liquid collects within the valve structure, means incorporated within said valve structure for normally establishing a fluid pressure within the valve which is not in excess of the fluid pressure within the flow tube, means whereby the valve will be over-balanced by the fluid when it is open, and spring means yieldably holding the valve in its closed position.

7. A fluid lift structure for wells comprising a closed chamber adapted to be submerged within the liquid of a well, a conduit through which a column of liquid may be carried from said closed chamber, means packing off the conduit against the wall of the well, a conduit conducting fluid under pressure to said column of liquid adjacent the bottom thereof, a valve element located within the structure establishing and interrupting the flow of said pressure fluid into said conduit, said valve element having movable means therein upon which the weight of the column of liquid will be imposed and by which weight only the valve will be opened when a predetermined hydrostatic head of liquid occurs thereabove, and means acting at the low point in the pumping cycle to reduce fluid pressure within the valve structure to a degree equal to the fluid pressure within the flow tube.

8. A fluid lift structure for wells comprising a

closed chamber adapted to be submerged within the liquid of a well, a conduit through which a column of liquid may be carried from said closed chamber, means packing off the conduit against the wall of the well, a conduit conducting fluid under pressure to said column of liquid adjacent the bottom thereof, a valve element located within the structure establishing and interrupting the flow of said pressure fluid into said conduit, said valve element having movable means therein upon which the weight of the column of liquid will be imposed and by which weight only the valve will be opened when a predetermined hydrostatic head of liquid occurs thereabove, means for establishing a predetermined resistance to the opening of said valve, and means acting at the low point in the pumping cycle to reduce fluid pressure within the valve structure to a degree equal to the fluid pressure within the flow tube.

9. A fluid lift structure for wells comprising a closed chamber adapted to be submerged within the liquid of a well, a conduit through which a column of liquid may be carried from said closed chamber, a conduit conducting fluid under pressure to said column of liquid adjacent the bottom thereof, a valve element located within the structure establishing and interrupting the flow of said pressure fluid into said conduit, said valve element having movable means therein upon which the weight of the column of liquid will be imposed and by which weight the valve will be opened when a predetermined hydrostatic head of liquid occurs thereabove and beneath which leakage liquid collects within the valve structure, and means for normally establishing a fluid pressure within the valve structure as low as the fluid pressure within the flow tube and whereby when the valve is opened it will be over-balanced so as to be temporarily held in its opened position.

10. A fluid lift apparatus for wells comprising a casing, a flow tube extending downwardly through said casing and being submerged in the liquid in the well, a standing valve in the bottom of said flow tube, packing means disposed in the space between the casing and the flow tube and forming a liquid pressure chamber therebelow and a pressure fluid chamber thereabove, a valve structure mounted in said flow tube above said packing means, said valve structure including a fixed element having ports for the passage of fluid from said lower chamber into a portion of said flow tube above said valve structure, walls forming passageways in said valve structure communicating with said pressure fluid chamber whereby fluid under pressure may flow into the portion of the flow tube above said valve structure, a valve element located within the valve structure and freely mounted in said valve structure and normally closing said passageways and beneath which leakage liquid collects within the valve structure, said valve element being adapted to move to an open position when a predetermined head of liquid has accumulated in said flow tube above said valve element, and means for balancing said valve element against fluid pressure by maintaining a fluid pressure within the valve structure in equilibrium with the fluid pressure in the flow tube.

11. A fluid lift structure for wells including a closed chamber adapted to be submerged in the liquid of a well, a flow tube extending downwardly into said chamber, a standing valve in said tube permitting only inflow of liquid from said chamber thereinto, a valve structure mounted in said flow tube, walls forming parts in said valve struc-

ture permitting an uninterrupted passage of a column of liquid from said chamber to said flow tube, walls forming a plurality of passageways in said valve structure adapted for the passage of a fluid under pressure to said flow tube above said valve structure, means for delivering fluid under pressure to said flow tube, a valve element located within the valve structure and normally interrupting the flow of fluid under pressure and acting under a predetermined weight of a column of liquid within the flow pipe to open and permit entry of fluid under pressure to said flow pipe below said column of liquid to lift the same and beneath which leakage liquid collects within the valve structure and means for balancing said valve element against fluid pressure by maintaining a fluid pressure within the valve structure in equilibrium with the fluid pressure in the flow tube.

20 12. A fluid lift structure for wells comprising a closed chamber adapted to be submerged within the liquid of a well, a flow tube extending downwardly into said chamber, a check valve therein permitting inflow of liquid from said chamber to the flow tube only, a valve structure within the flow tube and disposed below the level at which liquid will accumulate in the flow tube, said valve structure being formed with ports permitting an uninterrupted rise of a column of liquid through the valve structure and into the flow tube, means for delivering a fluid under pressure to said valve structure, a valve element normally interrupting the flow of fluid under pressure and acting under the weight of a predetermined column of liquid within the flow pipe to open and to permit the entry of gas to the flow pipe beneath said column of liquid to lift the same, walls forming a chamber in said valve structure adapted for the accumulation of fluid seeping thereinto, and means 25 for exhausting the fluid from said chamber during the low pressure period in each cycle of operation of said valve element.

13. A fluid lift structure for wells comprising a closed chamber adapted to be submerged within the liquid of a well, a flow tube extending downwardly into said chamber, a check valve therein permitting inflow of liquid from said chamber to the flow tube only, a valve structure within the flow tube and disposed below the level at which liquid will accumulate in the flow tube, said valve structure being formed with ports permitting an uninterrupted rise of a column of liquid through the valve structure and into the flow tube, means for delivering a fluid under pressure to said valve structure, a valve element normally interrupting the flow of fluid under pressure and acting under the weight of a predetermined column of liquid within the flow pipe to open and to permit the entry of gas to the flow pipe beneath said column of liquid to lift the same, walls forming a chamber in said valve structure, means for sealing said chamber, and means for exhausting the seepage fluid from said chamber.

14. In a device of the character described, a 65 valve structure including a movable valve element having a downwardly projecting portion, a valve body having an enclosed chamber into which said projecting portion of said valve element moves and whereby a fluid pressure is prevented from being exerted against the projecting portion of said valve element within the enclosed chamber and within which chamber fluid which has leaked around the valve element may be entrapped, a flow tube through which the fluid may 70 75

flow and within which said valve body is disposed, means for sealing said chamber while fluid is being forced through said flow tube, and means for exhausting accumulated liquid from said chamber and into said tube.

15. In a device of the character described, a valve structure including a valve body having an enclosed chamber, a valve element mounted for longitudinal movement in said chamber and within which chamber leakage fluid from around the valve element may pass and be entrapped, means for preventing a fluid pressure from being exerted against said valve element in said chamber, a flow tube within which said valve body is disposed and through and around which fluid may flow, means for sealing said chamber while liquid is being forced through said flow tube, and means for exhausting accumulated leakage liquid that has seeped within said chamber while the liquid was flowing.

16. In a device of the character described, a valve structure including a movable valve element having upper and lower projecting portions, a valve body having upper and lower chambers into which the projecting portions of said valve element are adapted to move and into which lower chamber leakage fluid may be entrapped, a flow tube through which fluid may flow, walls forming a plurality of ports in said valve body through which an uninterrupted flow of fluid from said flow tube may pass, walls forming a plurality of passageways in said valve body adapted for the passage of a compressible fluid to said upper chamber for elevating a column of liquid in said flow tube above said valve structure, means for sealing said lower chamber while liquid is being forced through the flow tube and from the well, and means for exhausting accumulated leakage liquid from said lower chamber, which liquid has entered said chamber while the liquid was flowing.

17. In a device of the character described, a valve structure, said valve structure including a

housing, a movable valve element therein co-operating with the housing to form a fluid chamber between the valve element and one end of the housing an inlet port opened by the valve 5 to admit pressure fluid into said housing, a tubing within which said housing is positioned and around which well fluid may flow to accumulate a slug of liquid thereabove within the tubing, a valved outlet establishing communication between 10 the housing chamber and the tubing, whereby the pressure of fluid within the chamber will exhaust after the slug of liquid has been forced from the well and will permit the fluid within the chamber and within the tubing to 15 equalize in pressure at a point in the flow cycle, after the slug of liquid has been discharged from the tube.

18. In a device of the character described, a flow tube, a well casing enclosing the same, a valve structure disposed within said tube and around which well fluids may rise to form a column of fluids within the tube, said valve structure including a housing, a movable valve element upon the end of which the well fluids accumulate, 20 yieldable means resisting the hydrostatic head of said fluids until the column has reached a predetermined height, ducts delivering a fluid under pressure through the valve housing from the well casing, said fluid being released into the flow tube when the column reaches a predetermined height, whereby the well fluids will be ejected from the flow tube as a slug of liquid, the lower end of the valve housing entrapping fluids passing around the valve and being normally closed, 25 and means acting at the low pressure point in the pumping cycle to permit the entrapped fluids at a pressure in excess of the pressure in the well to be relieved from the closed end of the valve housing, whereby fluid-locking of the valve is 30 prevented.

MARK P. BURKE.
